UNITED STATES PATENT OFFICE.

RALPH W. WHEELER, OF BROOKLYN, NEW YORK.

WIRE-WHEEL BRUSH.

1,326,815.

Specification of Letters Patent. Patented Dec. 30, 1919.

Application filed May 19, 1919. Serial No. 298,070.

To all whom it may concern:

Be it known that I, RALPH W. WHEELER, a citizen of the United States, residing at Brooklyn, in the county of Kings and State 5 of New York, have invented new and useful Improvements in Wire-Wheel Brushes, of which the following is a specification.

This invention relates to what is commercially known as wire wheel brushes, and 10 more particularly to that class wherein sections or brush units are employed of the desired diameter and weight according to the work to be performed and adapted to be arranged side by side in brush forming 15 relation and mounted upon a stock or standard form of hub.

Brushes of the class referred to are largely used by tool and hardware manufacturers and by finishers of various other kinds of 20 metal goods where buffing or polishing of a metallic surface is desired.

An object of the invention relates to a simplified manner and method of constructing the wire carrying units or sections of the 25 brush and the employment of such instrumentalities and certain niceties of construction whereby the sections or units can be completely formed by an automatic operation at a comparatively small cost and without resorting to the use of skilled hand 30 labor.

Another object of the invention relates to an improved method of constructing brush sections which will consist in the provision 35 of stock metal stripping which is adapted to be punched at suitable spaced intervals to accommodate the bristle bunches therethrough, the bristles being formed by feeding the bristle forming wires along one side 40 of the metal stripping and inserting or drawing the same through the punched portions of the stripping to provide suitable bristle bunches, the construction being such that on a complete feeding of the bristle 45 wires through one of such strips, the bights of the wire at the terminal of the bristle forming bunches can be mechanically clipped off to free the wire strands and cause the same to take a brush form.

50 Another object of the invention resides in the provision of metallic stripping having punched portions for the reception of the bristle forming wires therethrough, and the provision of marginal portions of the 55 stripping adapted to be upset against the

surfaces of the wire to maintain an operative retention of the wire to the stripping.

Another object of the invention is to provide a brush section formed of metal with marginal portions up struck to provide 60 bristle confining surfaces and to also constitute means whereby the ends of the section may be telescopically fitted together and thereby cause the section to operatively accommodate itself to a receiving hub of 65 a given external diameter.

Figure 1 is a side view of the brush section constructed in accordance with the invention.

Fig. 2 is a longitudinal section through 70 a portion of the strip showing the manner of threading the bristle forming wires therethrough.

Fig. 3 is a section on line 3—3 of Fig. 2.

In carrying the invention into practice, 75 use is made of what is commercially known as hoop stripping. I take a single length of stripping as shown at 5 and in the method or process of making the section, the strip may be fed automatically through any 80 suitable well known machine which will have incorporated therein a mechanism for punching the strip equi-distantly as at 2 so as to provide radial openings 3 for a purpose to be hereinafter explained. In the 85 present illustration, the punching is done on a straight longitudinal line but in this respect, I of course do not wish to be limited in that should it be desired, the openings formed by this method of punching may 90 be relatively staggered or otherwise arranged. The punching is performed between the sides of the strip so that the latter will be provided with bendable marginal portions 4 and 5. Progressively with the 95 operation of feeding and punching the strip, I feed the bristle forming wires over one side of the strip as shown particularly in Fig. 2, passing portions through the openings 3 to provide a group of bristles 6 and 100 7. I then fold the bristle wires at 7 to provide return bends and then again extend the wires through the openings 3 to provide second groups of bristles as shown at 8.

The connecting bights 9 between the groups 105 of bristles previously referred to are arranged in flat contact with the inner surface of the metallic strip as also shown in Fig. 2. After this operation is performed and the strip has been fully provided with 110

bristle forming wires, I bend the marginal portions 4 and 5 over against one another as illustrated in Figs. 3, clenching the same in close confinement with the bights 9 previously referred to. By bending the portions 4 and 5 in this manner, provision is made whereby one end of the strip can be extended telescopically into the other end of the strip as shown in dotted lines in Fig. 1. The strip then assumes the ring form as shown in Fig. 1 whereby it will operatively accommodate itself with a receiving hub 11 of a given diameter. The ends of the strip may be welded or secured together in any suitable well known manner if desired. While the strip is in a straight length, after the bristle wires have been fed therethrough, the ends of the wires slightly within the return bends 7 of the respective groups 6 and 8 can be clipped off so as to expose the burnishing ends of the bristles as will be understood. However, this operation may be delayed if desired until the section has been arranged in ring form as shown in Fig. 1. The entire structure may then be placed under a suitable shearing cutter to eliminate the return bends 7 referred to.

The up-setting of the strip to provide the portion 2 is performed with that regard which will produce within the openings 3 relatively broad curved surfaces 12 so as to prevent possible shearing of the bristles when the brush is in operation.

The openings 3 are arranged with their walls in snug contact with the bristles so as to give rigidity to the bunches 6 and 8 at their juncture with the strip. This construction gives the proper measure of springiness to the bristles, combining with such springiness a suitable measure of rigidity to permit a highly efficient burnishing or polishing action when the brush is in operation.

The point in particular of the invention about which I desire to lay particular emphasis is the perforating of a stock strip,

preferably of the kind stated, feeding the bristle wires through the perforations thus formed so as to provide normally connected groups of bristles with return bends between said groups and then clipping said return bends to expose the effective burnishing or working extremities of the wires. The simplicity of this operation is quite appreciable over tedious and costly operations of separately bunching or spreading the bristles and applying the same to the ring. I wish also to lay some stress upon the simplicity of completing the operation of forming the brush, having in mind the bending over of the marginal portions 4 and 5 against the bights 9 of the wires. This is an extremely simple and efficacious means for operatively arranging the strip and the wires in secure confinement with each other.

What is claimed as new is:—

1. The herein described method of constructing brushes which consists in providing a perforated strip material, threading a single length of tuft or brush filling material through said perforations to provide outer return bends between the lateral branches, and connecting inner portions between said branches, arranging said inner portions against one face of the strip, bending the sides of the strip against said inner portions, and then clipping the return bends from the normally connected branches of the bristle material to render said branches relatively independent.

2. The herein described method of constructing brushes which consists in providing a perforated strip material, threading a single length of tuft or brush filling material through said perforation to provide normally connected groups of laterally arranged bristles, and then cutting the material at points inwardly of the return bends between said bristle groups.

In testimony whereof I have affixed my signature.

RALPH W. WHEELER.
